No. 643,435.

Patented Feb. 13, 1900.

N. M. WIG.

DETACHABLE GRAIN DRILL SHOE.

(Application filed Aug. 23, 1899.)

(No Model.)

FIG. 2.

FIG. 3.

UNITED STATES PATENT OFFICE.

NILS M. WIG, OF ALEXANDRIA, MINNESOTA, ASSIGNOR TO THE OWATONNA MANUFACTURING COMPANY, OF OWATONNA, MINNESOTA.

DETACHABLE GRAIN-DRILL SHOE.

SPECIFICATION forming part of Letters Patent No. 643,435, dated February 13, 1900.

Application filed August 23, 1899. Serial No. 728,250. (No model.)

To all whom it may concern:

Be it known that I, NILS M. WIG, of Alexandria, county of Douglas, State of Minnesota, have invented certain new and useful Improvements in Detachable Grain-Drill Shoes, 5 of which the following is a specification.

The object of this invention is to provide a grain-drill with a shoe that is readily detachable from the shoe-shank and drag-bars for 10 the purpose of permitting it to be polished or sharpened or a new shoe to be substituted therefor.

The invention consists generally in a grain-drill shoe that is detachable from the shoe-shank and drag-bars.

The invention consists, further, in the constructions and combinations hereinafter described, and particularly pointed out in the claims.

In the accompanying drawings, forming 20 part of this specification, Figure 1 is a side elevation of a grain-drill shoe embodying my invention. Fig. 2 is a plan view of the same. Fig. 3 is a vertical central section on line x x 25 of Fig. 2.

In the drawings, 2 represents the hollow shank of the shoe, through which the grain is dropped by the feeding mechanism of the drill. This shank is of the usual or any preferred size and form. A drag-bar 3, consisting 30 of two members preferably arranged a short distance apart, has its rear end riveted or otherwise secured to the lower end of the shoe-shank 2.

The shoe 5 is made separate from the hollow shank 2 and is provided with means for readily attaching it to the shank and drag-bar. The shoe 5 is of the usual form, having an open-ended recess into which the grain 40 falls from the hollow shank and out of the rear end of which the grain passes in the usual manner into the drill made by the shoe. Any suitable means may be employed for detachably securing the shoe to the drag-bar and shank. As here shown, the two members of 45 the guide-bar are separated, being held apart by a suitable plate or bar 7, which is held in

place by rivets 9, which pass through the two members of the drag-bar and through said plate. The shoe is provided at its forward 50 end with a projection 11, having a recess in its upper end adapted to engage a pin 15, extending between the two members of the drag-bar. Near the rear end of the shoe is a projection 17, secured to the shoe by a bolt or 55 rivet 19. The upper end of the projection 17 is provided with a hook 21. An eccentric locking-lever 23, provided with a pin 25, is adapted to engage the hook on the projection 17. By turning the lever from the position 60 indicated in full lines in Fig. 3 to the position indicated by full lines in Fig. 1 the shoe is drawn firmly against the under side of the drag-bar and is firmly locked into position. I may also provide a projection 29 on the lower 65 end of the hollow shank 2, that extends into the recess in the shoe, as shown in Fig. 3, and helps to hold the shoe in proper position.

The entire shoe, it will be seen, is readily detachable and may as readily be replaced. 70 If the shoe becomes dull, it may be taken off and ground or sharpened and replaced. No tools are necessary either for removing or replacing the shoe. If a shoe becomes broken, a new one may be substituted therefor.

I do not limit myself to the particular devices shown for detachably securing the shoe in position, as the same may obviously be varied in many particulars without departing from my invention.

Having thus described my invention, I claim as new and desire to secure by Letters Patent—

1. The combination, with a grain-drill-shoe shank and drag-bar, of a removable shoe and 85 means for detachably securing said shoe to said shank and drag-bar, for the purpose set forth.

2. The combination, with a hollow grain-drill-shoe shank, of a shoe and means for detachably securing said shoe to the lower end 90 of said shank, for the purpose set forth.

3. The combination, with the hollow shoe-shank and the drag-bar having its rear end

connected to said shoe-shank, of the removable shoe and means for detachably securing said shoe to said shank and drag-bar.

4. The combination, with the hollow shoe-shank 2, of the drag-bar consisting of two members suitably separated and having its rear end connected to the lower end of said hollow shank, the removable shoe 5 provided with projections adapted to extend between

the members of said drag-bar and means for detachably securing said shoe to said drag-bar, for the purpose set forth.

In witness whereof I have hereunto set my hand this 17th day of August, 1899.

NILS M. WIG.

In presence of—
NILS E. JOHNSON,
F. H. STEVENS.
